UNITED STATES PATENT OFFICE.

OTA CROSTHWAIT, OF KANSAS CITY, MISSOURI.

DESIGN FOR A DOLL.

Application filed May 11, 1925. Serial No. 13,396. Term of patent 3½ years.

To all whom it may concern:

Be it known that I, OTA CROSTHWAIT, a citizen of the United States, residing at Kansas City, in the county of Jackson and State of Missouri, have invented a new, original, and ornamental Design for a Doll, of which the following is a specification, reference being had to the accompanying drawing forming part thereof.

Fig. 1 is a front elevation of my new design for a doll.

Fig. 2 is a rear elevation of the same.
I claim.

The ornamental design for a doll, as shown.

OTA CROSTHWAIT.
